UNITED STATES PATENT OFFICE.

EDWIN BALTZLEY, OF PHILADELPHIA, PENNSYLVANIA, ASSIGNOR TO THE KEYSTONE MANUFACTURING COMPANY, OF SAME PLACE.

MOTOR FOR CULINARY BEATERS, MIXERS, &c.

SPECIFICATION forming part of Letters Patent No. 403,502, dated May 21, 1889.

Application filed May 11, 1888. Serial No. 273,615. (No model.)

To all whom it may concern:

Be it known that I, EDWIN BALTZLEY, a citizen of the United States, residing at Philadelphia, in the county of Philadelphia and State of Pennsylvania, have invented certain new and useful Improvements in Motors for Culinary Beaters, Mixers, &c.; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to devices for mixing, kneading, creaming, and beating, and has for its object the provision of a base or support for the vessel which will have a combined rotary and reciprocatory motion, whereby every part of the vessel will be brought under the action of the beater, which is yielding or flexible, so as normally to fill the vessel when the center of the vessel comes nearly or directly opposite the center of the beater. Now, when the vessel travels back and forth within certain limits, which are adjustable, the beater will be crowded against the side of the vessel with a greater or less degree of tension; but as the vessel rotates simultaneously with its reciprocating motion its position is constantly changing relatively to the beater. Thus it will be understood that each and every side of the vessel will come in contact with or be crowded against the beater. The base rotates in the same direction whichever way it is traveling.

The improvement consists of the novel features hereinafter more fully described and claimed, and shown in the accompanying drawings, in which—

Figure 1 is a side view, parts being broken away, of a device embodying my invention; Fig. 2, a front view, parts being broken away, of the device; Fig. 3, a top plan view, parts being broken away, of the base or support; Fig. 4, a vertical section about on the line Z Z of Fig. 3; Fig. 5, a cross-section on the line X X of Figs. 3 and 4; Fig. 6, a detail perspective view of the tappets and the adjusting-screw, showing part of the guideway for the

tappets; Fig. 7, a perspective view of the arm which is connected with the shipper-lever, showing the means for connecting the tappet-adjusting screw or rod therewith.

55

The bed A of the device is provided with ways or tracks a, on which the stand or table B is mounted and guided in its reciprocating movements, and has side sockets, a', in which are fitted the lower ends of the standards C, which are bolted therein. The cap or cross piece D, that unites the upper ends of the standards, supports the beater adjusting and driving devices. The beater E, of ordinary construction and adapted to contract and expand in its circumferential length, is secured to the lower end of the shaft e, which has its upper end connected with the rack-bar F. The pinion f, meshing with the rack-bar F and keyed to a shaft controlled by the hand-wheel F', serves to move the rack-bar vertically and elevate and lower the beater.

60

F² is a locking device, of ordinary construction, to hold the hand-wheel against movement when the beater is adjusted to the proper position. The transverse shaft G, having band-pulleys G' on its outer end and bevel-pinion g on its inner end, which is in mesh with the bevel-pinion e', through which the shaft e moves, transmits motion to the beater 65 from the shaft H through the endless belt g' and the speed-cone g² on the outer end of the shaft H. The bevel-pinion e', journaled in the cross-piece D and having the shaft e, having an endwise or vertical movement through 70 the said pinion, is caused to revolve with the same by any well-known means—as by a feather-and-spline connection; or the shaft 75 may be angular in cross-section and the opening in the pinion of corresponding shape, as 80

85

will be readily understood. The shaft H, journaled transversely of the bed in suitable bearings, is provided at the end opposite the speed-cone g² with a band-pulley, h, and between its ends with two idle-pinions, h' and h², having half-clutches on their opposing ends, which are adapted to be engaged by corresponding half-clutches on the ends of the clutch-sleeve I, which is mounted on the shaft H between the said pinions h' and h² and keyed by a feather-and-spline connection to revolve with the shaft, 95

100

but free to move thereon between the pinions to engage with the one or the other, as may be required. The feed-screw J, journaled at its ends, is provided at its inner end with 5 the pinion j , which is in mesh with the pinions h' and h^2 and passes through a nut, j' , secured to the under side of the table B.

The shipper-lever K, having a pin, k , at one end, which fits in the annular groove i in the 5 clutch-sleeve I, is mounted at its outer end on the vertical stud K', so as to move therewith. The lower end of this stud K' has the arm L secured thereto, which extends at right angles to the shipper-lever K. The weighted lever M, journaled to operate in a vertical plane, has its lower end extended through a slot or opening, l , in the arm L, and its upper end provided with the weight m , which is adjustable thereon. This lever carries the arm 5 L past its dead-center and holds it in either position to keep the clutch-sleeve I close against the one or the other of the pinions h' and h^2 .

The tappet-rod N, having bearings in the 5 bed and in the block l' on the arm L, is provided with a right and left thread on its outer portion, on which the tappets n and n' are mounted, and has a crank, N', on its outer end for turning it and adjusting the tappets 50 o closer together or farther apart to regulate the travel of the table B. This rod is adapted to move longitudinally and carry with it the arm L. The ends of the tappets are extended and work between the plate O and the bed, 5 which guide them in their movement and prevent them being carried around with the rod N when it is rotated to adjust the tappets.

The stop P, projecting from the table B and extending within the path of the tappets, engages with each tappet alternately and moves the rod N in the direction of its length, and shifts the arm L and lever K, and moves the clutch-sleeve from one to the other pinion, thus changing the direction of motion of the 5 feed-screw J from right to left, and vice versa. If the shipper-lever K were changed solely by the moving action of the stop P on the rod N, the clutch-sleeve would be brought in contact with the pinions so slowly that a rupture of the parts would be likely to occur. To obviate this difficulty, the weighted lever M is provided, which, when started from one position to another, moves quickly after it passes beyond a perpendicular position and 5 carries the clutch-sleeve into engagement with the pinion quickly.

The turn-table Q, mounted on the table B and adapted to rotate thereon, is held thereon by the bolt q . The central enlargement, q' , of the turn-table fits within the depression b of the table B. The two pawls R, arranged diametrically opposite to each other and acting on opposite sides of the turn-table, have two heads, r , each adapted to engage with the 5 teeth q^2 , formed on the periphery of the turn-table Q. The pawls are pivoted at opposite ends relative to each other, and one only acts

on the turn-table at a time, and each of the pawls is held in engagement with the turn-table by a spring, S, coiled about the pivotal support of the pawl and having its ends extended, one end of the spring bearing against the standard and the other end of the spring bearing against the pin r' , depending from the pawl R. 75

The table B is mounted on rollers b' , which travel on the ways a . These rollers are held between pairs of lugs depending from the table.

In practice the vessel T, containing the 80 substance to be treated, is placed on the turn-table, and the beater is lowered to the requisite position by the rack-bar F, pinion f , and hand-wheel F'.

Motion is imparted to the device by applying power to the band-wheel h , which drives the shaft H, the beater E, through the means hereinbefore described, and the feed-screw J, through the clutch-sleeve K, one of the pinions, h' h^2 , and the pinion j . The motion of 85 the screw impels the support in one or the other direction, according to the direction of the motion of the said screw. When the table nearly reaches the limit of its travel, the stop P thereof engages with one of the tappets 90 and effects a longitudinal movement of the rod N, which movement is accelerated by the weighted lever M, as hereinbefore mentioned, and shifts the clutch-sleeve I from one to the other of the pinions and reverses the motion 100 of the screw, and consequently the direction of travel of the table, until said stop engages with the other tappet, when the motion of the screw and table will again be reversed, and so on, as will be readily understood. During 105 the reciprocating movement of the table one of the pawls will engage with the teeth q^2 of the turn-table and rotate it, the other pawl at the same time riding over the said teeth.

Now, when the motion of the table is reversed, the pawl previously idle will engage with the teeth and continue to rotate the table and the pawl previously active will now be idle. Thus the pawls act alternately on the turn-table and effect a continuous rotary 115 movement thereof. When the travel of the table is considerable, one head of the pawl will be thrown out of engagement with the teeth and the other head will be brought in engagement with the said teeth, as will be 120 readily comprehended. The length of travel of the table is regulated by varying the distance apart of the tappets, which is accomplished by rotating the screw-threaded tappet-rod N. 125

Having thus described my invention, what I claim, and desire to secure by Letters Patent, is—

1. The combination, with the bed, the table, means for reciprocating the table on the bed, and the shipper-lever, of the tappet-rod having a right and a left thread, journaled in the said bed and adapted to have a longitudinal and a rotary movement, the inner end

of the rod being in connection with the shipper-lever, the tappets mounted on the said rod and moved to and from each other by rotating the rod, and means, as the crank N', 5 for rotating the said tappet-rod, substantially as and for the purpose specified.

2. The combination of the bed, the table Q, having a stop, P, the feed-screw, means for rotating the feed-screw alternately in opposite directions, the shipper-lever, the arm L, connected with the shipper-lever, having the opening l in its end, the stud K', pivoted to the arm L, the tappet-rod journaled at one end in the stud K' and at its other end in the bed and having a right and a left thread, the tappets mounted on the threaded portions of the tappet-rod and having extensions, the guide-plate O, and the weighted lever M, having its end fitted in the opening l in the arm 15 L, substantially as described.

3. The combination of the bed and the reciprocating table having a stop, of the tappet-rod journaled in the bed and having a right and a left screw-thread thereon, the tappets 25 mounted on the threaded portions of the said rod and having extensions, and the plate O, forming a guide between it and the bed for the said extensions, substantially as described, for the purpose specified.

30 4. In a motor for mixers, beaters, &c., the combination of the reciprocating table, the turn-table carried by the said reciprocating table and having teeth about its periphery, and the two diametrically - opposite pawls, 35 each having two heads which alternately engage with the turn-table to produce a contin-

nous rotatory movement of the same simultaneously with its reciprocating movement, the head of one pawl engaging with the said teeth the moment the other head of the same 40 pawl is disengaged, substantially as set forth.

5. The herein-described machine for mixers, beaters, &c., composed of the bed A, having the standards C, the vertical shaft e, journaled in the cross-piece uniting the ends of 45 the standards and provided with the beaters at its lower end, the shaft H, gearing connecting the shaft H with the said shaft e, the pinions h' and h² on the shaft H, the double clutch-sleeve I, for keying one or the other of 50 the pinions h' and h² on the shaft H, the screw J, having pinion j on its outer end, which is in mesh with pinions h' and h², the rotatable and endwise-movable rod N, having a right and a left screw-thread thereon, the tappets 55 mounted on the threaded portions of the rod N, the shipper-lever K, connected with the rod N, the weighted arm M, the table B, engaged by the screw J and having a stop to engage with the said tappets, the turn-table 60 Q, having ratchet-teeth on its periphery, and the pawls R R, for engaging with and rotating said turn-table during its reciprocating movements, substantially as set forth, and for the purpose described. 65

In testimony whereof I affix my signature in presence of two witnesses.

EDWIN BALTZLEY.
